UNITED STATES PATENT OFFICE.

JAMES WILKINSON, OF SCHENECTADY, NEW YORK, ASSIGNOR TO GENERAL ELECTRIC COMPANY, A CORPORATION OF NEW YORK.

VALVE MECHANISM.

1,325,223.

Specification of Letters Patent. Patented Dec. 16, 1919.

Application filed November 23, 1917. Serial No. 203,501.

To all whom it may concern:

Be it known that I, JAMES WILKINSON, a citizen of the United States, residing at Schenectady, in the county of Schenectady, State of New York, have invented certain new and useful Improvements in Valve Mechanism, of which the following is a specification.

The present invention relates to valve mechanisms and has for its object to provide an improved valve mechanism embodying a number of new features and combinations of great utility.

For a consideration of what I believe to be novel and my invention, attention is directed to the accompanying specification and the claims appended thereto.

In the present instance I have shown my improvements as embodied in a valve mechanism of the so-called combined trip and throttle type, particularly intended for use in controlling the flow of elastic fluid to a turbine. As will appear hereinafter, some features of my invention are directed particularly to valve mechanisms for this general purpose, while other features are of more general application.

In the drawing, Figure 1 is an elevation partly in section of a valve structure embodying my invention; Fig. 2 is a sectional view on a larger scale of a portion of the stem structure and valve actuating parts, and Fig. 3 is a view showing the valve actuating parts in a position different from that shown in Fig. 1.

Referring to the drawing, 5 indicates a casing having an inlet 6 and an outlet 7. In the casing is a wall 8 which defines an opening 9 in which is located a cylinder 10 provided with a beveled edge forming a valve seat 11. The valve comprises a curved annular wall 12 which terminates in a head 13 on which is a face 14 adapted to engage valve seat 11 when the valve is in closed position. When the valve which is herein-after termed the main valve, is open the curved wall 12 and cylinder 10 define a Venturi-shaped passage 12^a through which the fluid flows in passing from the inlet 6 to the outlet 7. Carried by the valve head 13 is an annular wall 15 which slides in a cylinder 16 formed integral with a removable wall 17 of the valve casing. The head 13 and annular wall 15 thus form in substance a piston movable in cylinder 16.

Surrounding an opening through the central portion of head 13 are two oppositely extending cylinders 18 and 19. In cylinder 18 is a pilot valve seat 20, and on its outer end is a closing cap 21, and in cylinder 19 is a second pilot valve seat 22 formed on the end of a member 23 and spaced from valve seat 20. Between the two valve seats 20 and 22 is thus provided a pilot valve chamber 24 in which is located a pilot valve 25. The pilot valve chamber 24 is connected to the interior of cylinder 16 by a passage 26, and when the pilot valve is against seat 20, as shown in Fig. 1, the interior of cylinder 16 is connected by passage 26, chamber 24, and one or more passages 27 which are located in cross pieces 28, to the throat of the Venturi-shaped passage 12^a. When the pilot valve 25 is against seat 22, communication between passages 26 and 27 is cut off and the interior of cylinder 16 is then connected by passage 26, chamber 24, and a passage 29 formed in a rib 30 on head 13, to the admission side of the valve casing. Connected to member 23 is a hollow operating rod 31 which extends to the outside of casing 5 through a packing sleeve 32. The member 23 and rod 31 form in substance a single rod which is rigidly connected to the main valve and slides through the sleeve 32 to move such valve. Sleeve 32 is made comparatively long extending some distance both inside and outside the casing 5. It may be formed as an integral part of the casing 5, or as a separate part attached thereto by a flange 33, as shown. The rod 31 is provided with packing grooves 34 to prevent leakage and the packing sleeve is made long, as shown, so as to offer the greatest resistance to leakage. At its outer end the packing sleeve 32 is counterbored to provide a seat 35, and the outer end of rod 31 has an enlarged head 36 which slides in the counterbored end of sleeve 32, and is provided with a seat 37 which engages seat 35 when the valve mechanism is fully open, as shown in Fig. 1. Under these circumstances, it will be seen, leakage between the packing sleeve 32 and rod 31 is positively prevented. Connected to pilot valve 25 is a stem 38 which extends entirely through rod 31 and is provided on its end with a head 39 having a beveled face 40 thereon adapted to engage a seat 41 in the end of rod 31 to prevent leakage between the two.

When face 40 is held in engagement with seat 41, the pilot valve 25 is in engagement with seat 20. When the pilot valve is in this position and the main valve is either 5 fully open, as shown in Fig. 1, or partially open, the pressure behind the main valve in cylinder 16 is the pressure found at the throat of the Venturi passage 12^a, such pressure being conveyed to the cylinder through 10 passages 27 and 26. The pressures on the two sides of the main valve are thus the same, and the valve will be substantially balanced, although there will be slight excess 15 of pressure in a direction acting to move the valve to closed position due to the rod 31 which passes out through the valve casing, and is thus exposed at one end to atmospheric pressure. As is well understood, the extent of unbalancing of the valve would depend on the area of the end of rod 31 and the difference in pressure on the two ends of 20 the rod. The pressure at the throat of the Venturi passage is less than the pressure on the admission side of the valve casing due 25 to the fact that a certain amount of pressure is converted into velocity when a fluid flows through a Venturi passage. The drop in pressure, as is well known, depends on the amount which the Venturi passage converges. The pressure on the lower side of 30 the pilot valve 25 is that found at the throat of the Venturi, and the pressure on the lower side of the stem 38 is atmospheric pressure, since the stem passes out through casing 5. 35 The pressure on the upper side of valve 25 and on the upper end of stem 38 is that found on the inlet side of the valve, such pressure being conveyed through passage 29. The valve 25 is thus biased toward the seat 40 22. If it be considered that the stem 38 and rod 31 are held in fixed relation to each other with the pilot valve 25 in the position shown in Fig. 1, then the main valve can be opened or closed, or moved to any intermediate position 45 by moving the rod 31, the stem 38 of course, moving simultaneously therewith. In this manner the main valve can be used as an ordinary throttling valve and set to any position. If at any time the pilot valve 50 25 is moved relative to the main valve so as to bring it into engagement with valve seat 22, then the passages 27 are shut off and the interior of cylinder 16 is subjected to the pressure on the inlet side of the valve casing 55 through passages 29 and 26, which pressure is higher than that at the throat of Venturi passage 12^a. The main valve will thus become unbalanced since the pressure on the lower side of the valve is that found 60 at the throat of the Venturi passage. The main valve will therefore move toward closed position. It will thus be seen that by means of the pilot valve the main valve may be automatically adjusted to any desired intermediate position, the pilot valve being

moved back against seat 20 when the desired movement has been effected. In this same manner, if the pivot valve is moved against seat 22 and maintained there, the main valve will be automatically forced to closed position. It will be seen that I obtain the unbalancing of the main valve to close it by means of the use of the Venturi passage 12^a through which the fluid passing through the valve flows. This provides a simple fluid actuated means for closing the valve and does away with the use of springs or weights, or of any outside source of pressure. 70

The main valve rod 31 and the pilot valve stem 38 may be connected with various arrangements of actuating mechanisms for controlling the movements of the main valve and pilot valve according to the particular application to which the valve structure is to be put. When the valve structure as described is to be used as a combined trip and throttle valve, I preferably use a novel form 80 of controlling mechanism, as follows:

The outer end of rod 31 is squared, and projecting from the squared end is a segment 42 having teeth 43 along its edge. Projecting from two opposite sides of the squared end of rod 31 are two studs 44 upon which is pivoted a pilot valve actuator comprising two plates 45. The plates are held 90 in place on the studs by suitable nuts 46 and between the studs and the plates are eccentric sleeves 47 having fingers 48 by means of which they may be turned to adjust the pilot valve actuator, as is referred to hereinafter. 95 The outer ends of plates 45 are pivoted in spaced relation to each other on the end of an arm 49 having a nose 50 extending at an angle thereto and connected to segment 42 by a link 51. Nose 50 and link 51 thus form 100 a toggle. The plates 45 are provided with short curved slots 52 into which project studs 53 carried by the head 39 on the end of stem 38. When the arm 49 is swung toward the left the toggle comprising nose 50 and link 51 will be broken and the plates 45 will be 105 swung toward the left. This forces the curved slots 52 along studs 53 and moves the pilot valve and its stem to a position where the pilot valve engages seat 22. This position of the plates 45 and arm 49 is shown 110 in Fig. 3. The plates 45 are also spaced apart by a collar 54 through which extends a pivot pin 55, the ends of which project beyond the plates. Pivoted on the ends of pin 115 55 at its elbow is a bell crank hand lever 56, one end of which is in the form of a handle 57. The other end of lever 56 is pivotally connected to the stationary sleeve 32 by a link 58, thus forming a toggle which may be 120 straightened out, as shown in Fig. 3, to close the main valve. The one end of hand lever 56 is forked to straddle the segment 42, and the two members of the fork are held on the ends of pins 59 by suitable nuts 59. Piv- 130

oted within the hand lever 56, directly over the teeth on segment 42 is a catch 60 having one or more teeth which engage the teeth 43. The catch 60 is provided with short journals 5 which project through openings in the lever 56 and are rigidly connected at their ends by a U-shaped member 61 which is connected by a rod 62 to a usual form of catch lever 63. When the catch lever 63 is moved on its 10 pivot by grasping the handle 57 the rod 62 pulls on the U-shaped member 61 and turns the catch 60 on its journals through an angle of about 90° out of engagement with teeth 43. Since the hand lever 56 is pivoted on 15 plates 45 the catch 60 also moves out of engagement with teeth 43 when plates 45 are swung toward the left to move pilot valve 25. 64 indicates a drain opening and 65 a grease cup.

20 When the arm 49 is in the position shown in Figs. 1 and 2, the toggle comprising nose 50 and link 51 is straightened out and the pilot valve 25 is held against seat 20. Also, the seat 40 on head 39 is held against seat 25 41. The studs 53 are at one end of slots 52. The effective length of the plates 45 may be varied by turning the eccentric sleeves 47 so as to obtain correct seating of the pilot valve 25 and valve seat 40. The pilot valve 25 and 30 its stem 38 are thus positively locked to rod 31 to move therewith. The main valve may now be opened or closed or moved to any intermediate position by means of hand lever 56, such lever acting to move the rod 31 through the toggle formed by the bent end 35 of lever 56 and link 58, and it may be fastened in such position by catch 60 engaging segment 42. As already explained, when the pilot valve 25 is in this position the main 40 valve is substantially balanced. When the main valve is partially or wholly open the pressure on its opposite sides is that at the throat of Venturi passage 12^a; when closed it is that on the discharge side of the valve 45 casing. The main valve is always biased toward closed position, or when closed held in such position by the pressure on the upper side of pilot valve 25 and stem 38. If, when the valve is closed, it is desired to have a 50 greater force holding it closed, the arm 49 may be moved to shift the pilot valve over against seat 22 which will close off passages 27 and admit the pressure on the admission side of valve casing 5 to cylinder 16. Now 55 to again open the main valve, the pilot valve 25 would be moved back to its former position against seat 20, thus relieving the pressure in cylinder 16 after which the main valve is opened by lever 56.

60 If at any time when the main valve is in an open position it is desired to quickly close the same, the arm 49 is swung toward the left turning plates 45 and forcing slots 52 along studs 53, thus moving the pilot 65 valve 25 to a position where it engages seat

22, and at the same time swinging hand lever 56 bodily toward the left to disengage catch 60 from teeth 43. This latter results from the fact that hand lever 56 is fulcrumed on plates 45. The movement of the 70 pilot valve 25 into engagement with slots 22 admits the pressure existing on the admission side of casing 5 to cylinder 16, which pressure being greater than that at the throat of the Venturi passage 12^a 75 quickly forces the main valve to closed position. The positions which the valve operating parts assume under these conditions is shown in Fig. 3. To again open the main valve the arm 49 is first moved to bring the 80 pilot valve back against seat 20 thus relieving the pressure in cylinder 16. This, of course, swings plates 45 toward the left and brings catch 60 back into engagement with teeth 43. The main valve may then be 85 opened, as already explained.

The arm 49 may be operated manually, but when the valve mechanism is used in connection with a prime mover, for example, an elastic fluid turbine, for controlling the 90 flow of motive fluid thereto, the arm 49 will be connected with the emergency governor of the prime mover so that in case of excess speed the arm 49 will be moved to cause the main valve to automatically close, thus shutting down the machine. In Fig. 1, 66 indicates a rod which may lead to such an emergency mechanism and be moved by it in the ordinary and well-known manner to trip the 95 valve mechanism.

100 In accordance with the provisions of the patent statutes, I have described the principle of operation of my invention, together with the apparatus which I now consider to represent the best embodiment thereof; 105 but I desire to have it understood that the apparatus shown is only illustrative, and that the invention can be carried out by other means.

What I claim as new and desire to secure 110 by Letters Patent of the United States, is:—

1. In a valve mechanism, the combination of a casing having a seat therein, a main valve adapted to engage the seat, a wall so arranged that when the main valve is open 115 there is formed a Venturi shaped passage through which the fluid flows in passing through the main valve, a cylinder, a piston connected to the main valve and located in said cylinder, conduits which connect the 120 cylinder to the throat of the Venturi shaped passage and to the admission side of the valve casing, and a pilot valve means controlling said conduits.

2. In a valve mechanism, the combination of a casing having a seat therein, a main valve adapted to engage the seat, a wall so arranged that when the main valve is open 125 there is formed a Venturi shaped passage through which the fluid flows in passing 130

through the main valve, a cylinder, a piston connected to the main valve and located in said cylinder, conduits which connect the cylinder to the throat of the Venturi shaped passage and to the admission side of the valve casing, a pilot valve controlling said conduits, a rod for moving the main valve, a stem for the pilot valve, said stem and pilot valve being movable independently of 10 the main valve and its rod, and means for locking said stem and rod together.

3. In a valve mechanism, the combination of a casing having a seat therein, a valve adapted to engage the seat, said valve when open defining a Venturi-shaped passage through which the fluid flowing through the valve passes, a piston and cylinder associated with the valve for moving it, a pilot valve, and conduits controlled by the pilot valve for connecting the cylinder to either 20 the throat of the Venturi section or to a region of different pressure.

4. In a valve mechanism, the combination of a casing, a valve therein, the contour of 25 said valve and casing being such as to form a Venturi-shaped passage when the valve is open, a cylinder in which the valve slides, a conduit connecting the cylinder to the admission side of the casing, a conduit connecting the cylinder to the throat of the 30 Venturi-shaped passage, and a pilot valve controlling said conduits.

5. In a valve mechanism, the combination of a casing provided with a central wall 35 having an opening therein, a cylinder in the opening having a seat thereon, a main valve adapted to engage the seat, said main valve having a curved wall which forms with said cylinder a Venturi-shaped passage 40 when the valve is open, a cylinder in which the head of the valve slides, conduits in the main valve which connect the cylinder to the admission side of the valve casing and to the throat of said Venturi passage, and a 45 pilot valve controlling said conduits.

6. In a valve mechanism, the combination of a casing, a main valve therein, a rod for moving it, a pilot valve associated with the main valve, a stem for the pilot valve, 50 means for fastening the pilot valve and its stem in fixed relation to the main valve and its rod, means for adjusting the main valve to any desired position, locking means for said adjusting means, and means connecting said pilot valve fastening means to said main valve locking means whereby when the pilot valve fastening means is released 55 said valve locking means will also be released and the main valve automatically closed.

7. In a valve mechanism, the combination of a casing, a main valve therein, a rod for moving it, a pilot valve associated with the main valve, a stem for the pilot 60 valve means for fastening the pilot valve

and its stem in fixed relation to the main valve and its rod, means for adjusting the main valve to any desired position, locking means for said adjusting means, and separate means for moving the pilot valve relatively to the main valve, said separate means being connected to said locking means. 70

8. In a valve mechanism, the combination of a main valve, a pilot valve, a lever for moving the main valve to any desired position, a segment over which the lever moves, a catch for locking the lever to the segment, and means for simultaneously moving said pilot valve and releasing said catch to close automatically the main valve. 75

9. In a valve mechanism, the combination of a valve casing, a main valve and a pilot valve therein, an operating rod connected to the main valve, a stem for the pilot valve, a pilot valve actuator pivoted on said rod 80 and connected to the stem, and a lever for operating the main valve which is fulcrumed on the pilot valve actuator and is connected by a link to a stationary portion of the valve casing thereby forming a toggle 85 through which the main valve is moved.

10. In a valve mechanism, the combination of a valve casing, a main valve and a pilot valve therein, an operating rod connected to the main valve, a stem for the 90 pilot valve, a pilot valve actuator pivoted on said rod and connected to the stem, and a lever for operating the main valve which is fulcrumed on the pilot valve actuator and is connected by a link to a stationary portion 95 of the valve casing, a segment over which the lever moves, and a catch on the lever which engages the segment, whereby when said pilot valve actuator is moved to move the pilot valve so as to cause the main 100 valve to close said catch is moved from engagement with the segment.

11. In a valve mechanism, the combination of a casing, a valve therein, an operating rod for the valve, a pivoted lever for moving the operating rod, a toothed segment, a catch pivoted to the lever in the plane of said segment for engaging the segment, means for moving the catch on its pivots to disengage it from the segment, and means 110 for moving the lever in the plane of the segment to disengage said catch.

12. In a valve mechanism, the combination of a valve casing, a main valve and a pilot valve therein, an operating rod connected to the main valve, a stem for the pilot valve, a pilot valve actuator pivoted on said rod and connected to the stem, and a lever for operating the main valve which is fulcrumed on the pilot valve actuator and 120 is connected by a link to a stationary portion of the valve casing, a segment on said rod over which the lever moves, a catch pivoted on the lever in the plane of the segment, and means for moving the catch 125

- on its pivots to disengage it from the segment, said catch being also moved from engagement with the segment when said pilot valve actuator is moved to move the pilot valve so as to cause the main valve to close. 5
13. In a valve mechanism, the combination of a casing, a main valve and a pilot valve therein, concentric members one of which is connected to the main valve and the other to the pilot valve, an actuator normally connected to one of said members, said actuator being provided with an angular slot, a pin on the other member which engages said slot, and an arm for moving said actuator to move the pilot valve relatively to the main valve. 10
14. In a valve mechanism, the combination of a casing, a main valve and a pilot valve therein, concentric members one of which is connected to the main valve and the other to the pilot valve, an actuator pivoted to one of said members, said actuator being provided with an angular slot, a pin on the other member which engages said slot, and an arm for oscillating said actuator to move the pilot valve and main valve relatively to each other. 15
15. In a valve mechanism, the combination of a casing, a main valve and a pilot valve therein, concentric members one of which is connected to the main valve and the other to the pilot valve, an actuator normally connected to one of said members, said actuator being provided with an angular slot, a pin on the other member which engages said slot, an arm for moving said actuator to move the pilot valve relatively to the main valve, means for locking said main valve in open position, and means whereby when said arm is moved to move the pilot valve it also actuates said locking means. 20
16. In a valve mechanism, the combination of a casing, a main valve therein, a pilot valve, means controlled by the pilot valve for automatically effecting the closing of the main valve, means for locking the main valve open, and means for moving said pilot valve and releasing said locking means whereby the main valve may be automatically closed. 25
17. In a valve mechanism, the combination of a casing, a main valve therein, a pilot valve, means controlled by the pilot valve for effecting the closing of the main valve, 30
- concentric members one of which is connected to the main valve and the other to the pilot valve, means for opening and closing the main valve, locking means for said last named means, an actuator for moving the pilot valve relative to the main valve, and means connecting said actuator to the locking means whereby when said actuator is moved to effect the closing of the main valve, it also unlocks said locking means. 35
18. In a valve mechanism, the combination of a casing, a seat therein, a valve adapted to engage the seat, said valve when open defining a Venturi shaped passage through which the fluid flowing through the valve passes, a piston and cylinder associated with the valve for moving it, a pilot valve, conduits controlled by the pilot valve for connecting the cylinder to either the throat of the Venturi section or to a region of different pressure, concentric members one of which is connected to the main valve and the other to the pilot valve, an actuator normally connected to one of said members, said actuator being provided with an angular slot, a pin on the other member which engages said slot, and an arm for moving said actuator to move the pilot valve relatively to the main valve. 40
19. In a valve mechanism, the combination of a casing, a seat therein, the valve adapted to engage the seat, said valve when open defining a Venturi shaped passage through which the fluid flowing through the valve passes, a piston and cylinder associated with the valve for moving it, a pilot valve, conduits controlled by the pilot valve for connecting the cylinder to either the throat of the Venturi section or to a region of different pressure, concentric members one of which is connected to the main valve and the other to the pilot valve, an actuator normally connected to one of said members, said actuator being provided with an angular slot, a pin on the other member which engages said slot, an arm for moving said actuator to move the pilot valve relatively to the main valve, means for locking said main valve in open position, and means whereby when said arm is moved to move the pilot valve it also actuates said locking means. 45
- In witness whereof I have hereunto set my hand this 21st day of November, 1917.
- JAMES WILKINSON. 50
